(57) **CLAIM**

The ornamental design for a rimless toilet pan, as shown and described.

DESCRIPTION

FIG. 1 is a perspective view taken from the top front and right side showing the rimless toilet pan;

FIG. 2 is a perspective view taken from the top rear and right side showing the rimless toilet pan;

FIG. 3 is a top plan view of the rimless toilet pan with section lines added;

FIG. 4 is a rear elevation view of the rimless toilet pan;

FIG. 5 is a left view of the rimless toilet pan with section lines added;

FIG. 6 is a front view of the rimless toilet pan;

FIG. 7 is a right view of the rimless toilet pan;

FIG. 8 is a bottom view of the rimless toilet pan;

FIG. 9 is a sectional view of the rimless toilet pan taken in the direction of line 9-9 of FIG. 3;

FIG. 10 is a sectional view of the rimless toilet pan taken in the direction of line 10-10 of FIG. 5; and,

FIG. 11 is a sectional view of the rimless toilet pan taken in the direction of line 11-11 of FIG. 5.

The drawings show the external parts of the pan in broken line in which the article embodying the design is used and forms no part of the claimed design. The drawings define the outer boundary of the claimed design in dash-dot line and form no part thereof.
